UNITED STATES PATENT OFFICE

CHARLES W. ADAMS, OF LOS ANGELES, CALIFORNIA

TENT

Application filed September 11, 1928. Serial No. 305,228

The present invention relates generally to tents and the like, and is particularly concerned with a supporting structure whereby such protective coverings, irrespective of size, 5 may be supported externally with complete disposal of poles, guys or the like therebeneath, to leave the covered ground space clear.

In considering the invention applied to a circus tent, the advantage of having the tent 10 interior free from supporting poles is particularly great, for acts and properties may then be arranged at desired locations without regard to the usual restrictions imposed by the positions of the poles. Furthermore, additional seating capacity is thus provided 15 and an unobstructed view of the entire interior of the tent may be had from any location therein. The present supporting means also may be applied with advantage to the 20 supporting of substantially horizontally extending canopies irrespective of size. Such canopies may be large enough to be used over ball parks or other areas of considerable extent. Following my invention these canopies are supported from poles around their 25 outer edges, and in such manner that provision may be made for pulling the canopies to one end of the field or normally protected area when not in use.

As applied to tents, the poles are arranged 30 around the outside thereof, and are securely guyed, the tent canvas being supported from the poles in such a manner that the essential 35 rigidity of structure is maintained and the tent insured against "blow downs". Additional advantages of the invention will be most readily understood from the following description of typical embodiments thereof, reference being made throughout the description 40 to the accompanying drawings in which

Figure 1 is a perspective view of a circus tent embodying my invention;

Fig. 2 is an enlarged transverse sectional 45 view of the tent;

Fig. 3 is an enlarged fragmentary section showing a preferred means of connecting the side pick-up lines to the tent canvas;

Fig. 4 is an enlarged fragmentary section 50 showing a preferred means of joining one of

the tent peaks with a center pick-up line through the use of a bail ring;

Fig. 5 is an enlarged perspective view of a bail ring supporting block clamped to a cross guy; and

Fig. 6 is a diagrammatic perspective illustration of the application of the invention to a horizontally extending canopy.

Referring particularly to Figure 1, the tent canvas is seen to embody two semi-circular 60 end sections E, and "middle" sections M, of which there may be any number accordingly to the length of tent desired, two being here shown for purposes of illustration. The sections are laced together along the lines indicated by numeral 10. In order to strengthen and support the canvas, a net work of rope is provided upon which the canvas rests and to which it is intimately fastened. The net work is seen to comprise a series of horizontally 65 extending band ropes 11, encircling the tent, and a plurality of rafter ropes 12 extending from the outer edges of the canvas to the top 70 of the tent.

A plurality of main poles 13 is erected 75 around the tent preferably in opposite relationship on each side of the tent. Footing for the poles is provided by means of mud blocks 14 which rest on the surface of the ground. The main poles are guyed in four 80 directions by means of main guys 15 extending outwardly and downwardly from the crown rings 16 of each pole to anchors embedded in the ground at 17, side guys 18 joined to the crown rings and connecting the 85 poles in series, and cross guys 19 which interconnect pairs of oppositely disposed poles such as illustrated in Fig. 1 at P and P'. The cross guys 19 may be connected directly to the crown rings, as shown in Fig. 2, and 90 tightened, for instance by turn-buckles 19a, or by any other suitable means for pulling the cross guys taut between the main poles 13. From the foregoing it will be seen that the 95 main poles are securely guyed to form a rigid supporting structure.

The tent canvas is supported essentially from the main poles by what may descriptively be termed pick-up lines. The points at which these lines are joined to a tent, of 100

the circus type shown in Fig. 1, may correspond, in general, to the points at which such tents are usually supported from their under side by means of poles. Thus in the usual 5 internally supported tent, the canvas is supported at the peaks or center points 22 by means of center poles, and at side points 23 and 24 by means of quarter poles.

As shown in Fig. 2, in the present type of 10 structure the center pick-ups 25 are joined to the peaks 22 and extend through blocks 26, suspended centrally from cross guys 19, through blocks 27 supported by one of the crown rings 16 to which the supporting cross guys are attached, and downward to cleats 28 where they are tied securely to the posts. The side pick-up lines 29 and 30 preferably 15 are joined to the canvas at points 23 and 24, respectively, at spaced intervals along band ropes 11, any two points of connection on one side of the tent preferably being out of 20 line with respect to rafter ropes 12. It is to be understood that pick-ups may be applied to the canvas at points other than those shown, the illustrated arrangement being 25 typical only. Lines 29 and 30 pass through blocks 27, which in the present instance necessarily contain a number of sheave wheels, and extend downward to cleats 32 where they are 30 tied.

In Fig. 3 I have shown a typical means for 35 connecting the side pick-up lines 29 and 30 to the canvas. An eye-bolt 33 extends through an opening formed by lapping the canvas around a ring 33a and through a plate 34, the eye bolt nut 35 bearing against the lower face of the plate. The looped end of the pick-up line is joined to eye bolt 33 by means of hook 36, as shown. The center pick-up lines 25 are 40 similarly joined to a hook 36a which projects through upper looped ends of bails 37a extending upwardly from bail ring 37 around which the canvas is lapped. Blocks 26 may be suspended from cross guys 19 by means of 45 clamps 38 as clearly shown in Fig. 5.

Erected beneath the outermost edges of the 50 tent is a series of side poles 40 guyed by means of lines 41 staked to the ground at 42. The stretches of canvas between side posts are also held by tent guys 43, preferably 55 staked in line with the side pole guys 41. I have provided additional means for securely 60 anchoring the tent to the ground by joining guys 41 and 43 at the ground, or their points of connection with the stakes 42, with a main ground line 45, surrounding the tent on the side guy stake line. Transverse ground lines 46 are placed on top of line 45, under mud blocks 14 of transverse pairs of poles such as P and P', and are fastened at their ends to the main guy anchors 17. It will be seen that by virtue of this construction, forces tending to pull upward on guys 41 and 43 are transmitted through cable 45 to the main poles and guys 15, and to anchors 17.

In Fig. 6 I have illustrated a top portion of a flat canopy structure suitable for use over ball parks or the like, and which is supported in a manner essentially similar to the structure of Fig. 1. The canvas is seen to be 70 made up of middle sections M' and an end section E', and the whole surrounded by main poles 13a, each guyed in four directions by means of main guys 15a, side guys 18a and cross guys 19b. Side poles 40a and side guys 75 41a are provided as in the previously described structure. The several pick-up lines 50, are individually attached to the tent at 80 suitably spaced points 51 and extend through blocks 52, suspended from cross guys 19b, and through blocks 53 suspended from the crown rings of the main poles. The ends of the pick-up ropes are anchored to suitable means on the posts as in the previously described instance.

In a canopy of the type shown in Fig. 6, 85 it may be desirable to support the canvas along ridge lines 55, to depress the canvas to form troughs at 56, and to slope the entire canopy toward one end of the structure to 90 permit water to drain readily from the top. I have shown typical means for pulling the canopy to one end of the supporting structure, in the form of longitudinally arranged lines 60, extending beneath the canopy along 95 ridges 55, and extending through pulleys 61, suspended from the horizontal cables 62 of poles 63, and downward to the ground. By 100 attaching the lines 60 to the canopy at either end thereof, as at 64 or 65 according to the direction in which the canopy is to be moved, and disconnecting the pick-up lines 50 at 51, the canopy may be collapsed to either end 105 of the supporting structure by pulling the downwardly extending portions of lines 60.

In view of the numerous forms of tents and 110 canopies to which the present type of supporting structure may apply, it will be understood the drawings and description are to be considered merely as illustrative of and not 115 restrictive on the broader claims appended hereto for various changes in design, structure and arrangement may be had without departing from the spirit and scope of said claims.

I claim:

1. In a structure of the character described, a tent canopy, a plurality of poles erected at spaced intervals about the outside of said canopy, and a pick-up line supported from each post and attached to the upper surface of the canopy to support the latter from above.

2. In a structure of the character described, an externally supported tent canopy, a plurality of poles erected at spaced intervals along the outside of said canopy, and a plurality of pick-up lines supported from each post and attached to the canopy at 125 spaced points thereon.

3. In a structure of the character described, a tent canopy, supporting means embodying a plurality of poles having main guys extending outwardly therefrom to ground anchors, side guys joining the poles in series at their upper ends, a cross guy interconnecting the upper ends of a pair of poles arranged on opposite sides of the canopy, and a pick-up line joined to said canopy and vertically supported from said cross guy.

4. In a structure of the character described having a tent canopy, supporting means embodying a plurality of poles having main guys extending outwardly therefrom to ground anchors, side guys joining the poles in series at their upper ends, a cross guy interconnecting the upper ends of a pair of poles arranged on opposite sides of the canopy, a pick-up line joined to said canopy and vertically supported from said cross guy, and a plurality of pick-up lines supported at the upper end of each post and attached to said canopy at spaced points thereon.

5. In a structure of the character described having a tent canopy, a plurality of poles erected at spaced intervals along the outside of said canopy and having a cross guy interconnecting the upper ends of a pair of poles disposed on opposite sides of the canopy, a plurality of pick-up lines attached to said canopy at spaced points thereon and extending upward through blocks mounted on the upper ends of said poles and downward to suitable anchor means on the poles, and a pick-up line attached to the canopy and extending upwardly and through a block suspended centrally from said cross guy, horizontally across to a guy supporting pole, and downward through a block mounted on the pole to suitable anchor means.

6. In a structure of the character described having a canopy, a plurality of tent guys joined to the edges of said canopy and anchored to the ground around the canopy, a main ground line connecting in series the ground ends of said tent guys, a pair of supporting poles arranged on opposite sides of said canopy and each adapted to rest on said main ground line, said poles each having an outwardly extending main guy joined to a ground anchor in line with the poles, and a transverse ground line connected to said anchors and extending beneath the poles and on top of said main ground line.

55 7. In a structure of the character described, a tent canopy, a pair of poles disposed at opposite sides of said canopy, a cable extending above said canopy and interconnecting said poles at their upper ends, and a pick-up line connected to the upper surface of said canopy at a point intermediate the sides thereof and extending vertically to a connection with said cable, said pick-up line serving as a direct vertical support for said canopy.

8. In a structure of the character described,

a substantially single piece tent canopy, a pair of poles disposed at opposite sides of said canopy, a cable above said canopy and interconnecting said poles at their upper ends, means for supporting said canopy from said cable at one point therealong, and means, independent of the first mentioned means, for supporting said canopy from its upper surface at a second point between the first mentioned supporting means and one of said poles, said canopy forming a trough extending horizontally and transversely to said cable between said points at which the canopy is supported.

9. In a structure of the character described, a substantially single piece tent canopy, a pair of poles disposed at opposite sides of said canopy, a cable above said canopy and interconnecting said poles at their upper ends, means for supporting said canopy from said cable at one point therealong, and means for supporting said canopy from said cable at a second point between the first mentioned supporting means and one of said poles, said canopy forming a trough extending horizontally and transversely to said cable between said points at which the canopy is supported.

10. In a structure of the character described, a substantially single piece tent canopy, a pair of poles disposed at opposite sides of said canopy, a cable above said canopy and interconnecting said poles at their upper ends, means for supporting said canopy from said cable at one point therealong, means, independent of the first mentioned means, for supporting said canopy from its upper surface at a second point between the first mentioned supporting means and one of said poles, said canopy forming a trough extending horizontally and transversely to said cable between said points at which the canopy is supported.

11. In a structure of the character described, a substantially single piece tent canopy, a pair of poles disposed at opposite sides of said canopy, a cable above said canopy and interconnecting said poles at their upper ends, means for supporting said canopy from said cable at one point therealong, means for supporting said canopy from said cable at a second point between the first mentioned supporting means and one of said poles, said canopy forming a trough extending horizontally and transversely to said cable between said points at which the canopy is supported and means for collapsing said canopy horizontally from above the area normally covered thereby.

In witness that I claim the foregoing I have hereunto subscribed my name this 25th day of July, 1928.

CHARLES W. ADAMS. 130
